UNITED STATES PATENT OFFICE.

FREDERICK SMITH, OF DARBY, PENNSYLVANIA.

PREPAYMENT GAS METER.

1,404,167.

Specification of Letters Patent. Patented Jan. 17, 1922.

Original application filed June 26, 1916, Serial No. 105,791. Divided and this application filed November 26, 1917. Serial No. 204,074.

To all whom it may concern:

Be it known that I, FREDERICK SMITH, a citizen of the United States, residing at Darby, in the county of Delaware and State of Pennsylvania, have invented new and useful Improvements in Prepayment Gas Meters, of which the following is a specification.

This application is a division of my application for Letters Patent, Serial Number 105,791.

My invention relates to new and useful improvements in prepayment gas meters, and has for its object to provide a prepayment mechanism so constructed and arranged as to prevent the fraudulent use thereof and to prevent an unscrupulous person from obtaining gas without paying for the same.

A further object of the invention is to construct a coin handling mechanism for the prepayment device, which always turns in the same direction, thereby preventing the withdrawal of the coin after the mechanism has been set to supply a certain amount of gas and also facilitating the operation of the device.

Another object of the invention is to provide means for throwing out of action the predetermining mechanism when the limit of its capacity has been reached, thereby preventing injury to the device.

A still further object of the invention is to provide for the overthrow of the predetermining mechanism should the gas controlled valve leak to prevent injury to the mechanisms.

Another object of the invention is to provide means for computing the gas used during any leakage of the controlled valve.

A further object of the invention is to provide a mechanism for prepayment meters for pre-calculating and post-calculating the amount of gas used.

Other objects of the invention will be more fully brought out in the following description.

With these ends in view this invention consists in the details of construction and combination of elements hereinafter set forth and then specifically designated by the claims.

In order that those skilled in the art to

which this invention appertains may understand how to make and use the same, I will describe its construction in detail, referring by numerals to the accompanying drawings forming a part of this invention, in which—

Figure 1, is a front elevation of the upper portion of a gas meter showing my improved prepayment device attached thereto.

Figure 2, is a plan view thereof, the top wall of the meter being removed to more clearly illustrate the construction.

Figure 3, is a side elevation thereof, a portion of the valve housing and a portion of the casing of the prepayment device being broken away to show the connection between the valve and the prepayment device.

Figure 4, is a side elevation of the meter having the prepayment device removed.

Figure 5, is an enlarged plan view of the sleeve and the connecting dog which connects the predetermining mechanism with the valve and which provides for the overthrow of said predetermining mechanism.

Figure 6, is a face view thereof.

Figure 7, is a section at the line 7—7 of Figure 6, looking in the direction of the arrow.

Figure 8, is an enlarged side elevation of the prepayment device, its cover or closure being removed to illustrate the interior construction.

Figure 9, is a section at the line 9—9 of Figure 8.

Figure 10, is a section at the line 10—10 of Figure 8, looking in the direction of the arrow.

Figure 11, is a section at the line 11—11 of Figure 9, looking in the direction of the arrow, showing the coin handling mechanism in position for admitting a coin.

Figure 12, is a similar view showing the coin handling mechanism turned to a different position and having the indicator removed.

Figure 13, is a section on the line 13—13 of Figure 8 of the upper portion of the prepayment device, looking in the direction of the arrow.

Figure 14, is a section on the line 14—14 of Figure 13, looking in the direction of the arrow, having parts of the mechanism and casing broken away and showing the posi-

tion of the coin drawer with relation to the chute and coin handling mechanism.

Figure 15, is a side elevation of the coin handling mechanism.

5 Figure 16, is a similar view at approximately right angles thereto.

Figure 17, is a section at the line 17—17 of Figure 15, looking in the direction of the arrow.

10 Figure 18, is a section at the line 18—18 of Figure 16, looking in the direction of the arrow; and

15 Figure 19, is an enlarged sectional view of the predetermining mechanism showing the manner in which it is connected to its shaft.

In carrying out my invention as here embodied 2 represents a gas meter having inlet pipes 3 and an outlet pipe 4 and provided with the ordinary diaphragm (not shown), 20 which transmits power and motion to the diaphragm shafts 5, these being connected by the joint levers 6 with the crank 7 mounted upon the shaft 8, the latter carrying a worm gear 9, which latter meshes with a gear 10 mounted on the indicator shaft 11, which is connected with the train of gears of the indicator or register 12, whereby the amount of gas used or passed through the meter is registered or indicated upon the 30 dials 13.

On the indicator shaft 11 is mounted the worm gear 14 which meshes with the gear 15 carried by the transfer shaft 16, said shaft being formed of two parts 17 and 18, the latter telescoping with the former, the parts being held in their adjusted positions by the set screw 19. One end of this shaft 16 is journaled in the bracket 20, and the other end is connected with the rate wheel shaft 21 40 in any suitable manner, said connection here shown as comprising a pin 22 passing through the end of the member 17 of the shaft 16, said pin registering with notches 23 in the socket 24 which is loosely connected with 45 the projecting end of the rate wheel shaft 21.

The inlet pipe 3 is provided with a valve casing 25 in which is situated the valve seat 26 having a valve 27 coacting therewith, the latter being pivoted by the stem 28 to the 50 arm 29 at 30, said arm 29 passing through an opening 31 in the valve casing and projecting into the housing 32 carried by the valve casing and in which is journaled the shaft 33, said shaft being properly packed 55 to prevent the escape of gas.

The foregoing description relates to a meter of ordinary construction, and describes the parts to which my improved prepayment device is attached, but does not relate to my invention as my device may be attached to any meter having similar parts.

34 represents the casing of my pre-payment device comprising a side wall 35 having holes 36 therein to register with the pins 37

on the meter, a rear wall 38, a front wall 39 and top and bottom walls 40 and 41, respectively, the open side of the casing being normally closed by the cover 42.

In the casing is formed an opening 43 which extends partly into the side wall 35 and partly in the rear wall 38, and through this opening projects the housing 32 when the casing is applied to the meter, and at the same time the trunnion 44 permanently carried by the casing projects through an opening 45 in one of the side walls of the meter, and on this trunnion is threaded the nut 46, thereby properly holding the casing in position, and said nut is held against accidental displacement by the lock nut 47.

The rate wheel shaft 21 is journaled in the trunnion 44, and the inner end of said shaft 21 is supported by the supporting arm 146 loosely pivoted upon the stationary rod 147, said supporting arm 146 being provided with a notch 48 adapted to register with the shaft 21. On the square portion of the shaft 21 is removably mounted the rate wheel 49, which is in the form of a gear and meshes with the gear 50 journaled upon the shaft 51 90 carried by the depending angular support 52 pivoted to the shaft 53 and provided with a slot 54 which registers with the rod 147. Said support 52 and the supporting arm 146 are each held in their adjusted positions by 95 means of a thumb nut 55 or its equivalent threaded upon the rod 147 and having a spacing member such as a washer 56 interposed between said support and the supporting arm.

100 The gear 50 carries a pinion 57 which is revolvable through said pinion, meshing with the gear 58 mounted on the shaft 53 from which depends the support 52. The gear 58 carries an intermittent or one toothed pinion 59 adapted to mesh with the intermittent gear 60, which is journaled on the shaft 61, said shaft being mounted in one of the walls of the casing and having its free or inner end supported by a supporting 110 arm or strap 62 carried by the shaft 53.

The intermittent gear 60 is provided with an extra long hub or bearing 63, and this carries a pinion 64 which coacts with the predetermining mechanism, or in other words 115 meshes with the double spiral or worm 65 having a single flange 66 at one end and a double flange 67 at the opposite end, the latter forming a groove 68 for a purpose to be hereinafter described.

120 The predetermining mechanism which comprises the double worm 65, the single flange 66 and the double flange 67 is mounted upon a shaft 69 journaled in the brackets 70 secured to the side walls 35 of the casing. The shaft 69 is provided a portion of its length with corrugations 71, said corrugations terminating some distance from one

end of the shaft to form the blank space 72 of the same diameter as the deepest portions of the corrugations.

In order that the shaft 69 and the predetermined mechanism may be revolved simultaneously I provide a pin 73 which is carried by the spiral and projects from the inner circumference thereof to coact or register with the corrugations 71.

- 10 The forward end of the shaft 69 passes through the forward bracket 70 and projects into an opening 74 in the coin handling mechanism as plainly shown in Figure 14. The coin handling mechanism is plainly illustrated in Figures 11 to 18 inclusive in which 75 denotes the body having a coin pocket or cavity 76 therein provided with a mouth 77 acting one time as the inlet and another time as the outlet.
- 20 The body is also provided with a transverse arcuate notch 78 which communicates with the coin pocket 76 and also with the groove 79 formed around a portion of the periphery of the body adjacent one face thereof, and at the opposite end of said groove is formed an opening 80 which communicates therewith and acts as the inlet to said groove. The edge 81 or the wall of the notch 78 opposite the end of the groove 79
- 25 acts as a stop and is adapted to coact with the pin 82 carried by the housing 83 of the coin handling mechanism and projects from the inner face thereof. Said pin 82 registers with the groove 79 at certain times and at other times projects into the space 84 between the face of the body and the front wall of the housing, and in order that the rotation of the coin handling mechanism may be stopped, when the pin 82 is out of registration with the groove 79, I provide a stop 85 which is carried by the body and projects from the face thereof as plainly shown in Figure 15.

The coin handling mechanism is revolved by the shaft 86 which passes through the front wall of the housing 83, and has mounted thereon the handle 87. From the housing of the coin handling mechanism runs a coin chute 88 which terminates a short distance above the money drawer 89 in the bottom of the casing, said drawer passing through an opening 90 in the front wall of said casing.

In the upper portion of the housing 83 is formed a coin slot 91 and the lower portion of said housing terminates short of the front wall of the casing and beyond this is situated the bridge 92, thereby forming a coin slot 93 which leads to the coin chute 88.

60 The body 75 of the coin handling mechanism carries a ratchet gear 94 with which coacts the pawl 95 pivoted as at 96 to the bridge 92 thereby preventing the coin handling mechanism from being turned but in

one direction as shown by the arrow on Figure 13, and on the ratchet gear is pivoted a dog 97 as at 98 which is provided with a pin 99 on the side of the pivot point opposite the nose of said dog, and this pin works in the arcuate notch 78 and adapted at certain times to lie across a portion of the coin pocket 76.

When a coin is placed in the coin pocket 76, said coin will engage the pin 99, forcing the same outward, thus operating the dog 97, causing the nose thereof to engage the ratchet pinion 100 which is carried by the shaft 69 and securely attached thereto.

The operation of the coin handling mechanism is as follows:

The handle 87 is turned in the direction of the arrow shown on Figure 13 until the coin opening 77 in the body 75 is in alignment with the coin slot 91 in the housing 83, at which time a coin may be inserted in the coin pocket 76. When the coin has been placed in the coin pocket the pin 99 on the dog 97 will be forced outwardly, causing the nose of said dog to engage the ratchet pinion 100 on the shaft 69.

The entire coin handling mechanism is then moved inward by sliding the same within its housing 83, until the body 75 passes beyond the pin 82, at which time the coin handling mechanism may be rotated in the direction shown by the arrow on Figure 13 until the stop 85 contacts with the pin 82, at which time the coin slot 77 will be at the bottom of the device and partially or wholly covered by the bridge 92 to prevent the coin dropping from the coin pocket.

During the rotation of the coin handling mechanism the dog 97 is in contact with the ratchet pinion 100 as shown by dotted lines in Figure 11, which will cause the rotation of the shaft 69 and likewise the double spiral. As the spiral is in mesh with the gear 64, which is held against rotation because of the intermittent gear 60 being locked, such rotation will cause the double spiral 65 to thread between the gear 64 and move forward along the shaft 69 or toward the coin handling mechanism thereby predetermined the amount of gas to be used.

When the parts are in this position and it is desired to place another coin in the device, the coin handling mechanism is moved outward or toward the front face of the housing 83, causing the opening 80 to pass by or register with the pin 82, until said pin is in alignment with the groove 79, which action will bring the coin slot 77 in the body 75 in alignment with the coin slot 93, permitting said coin to fall from the coin pocket and pass through the coin slot 93 into the coin chute 88, where it will slide downward and fall into the coin drawer 89.

After the coin has fallen from the coin

pocket 76, the coin handling mechanism may be rotated further in the same direction, for the stop pin 101 carried by the casing which is in the path of travel of a portion of the dog 97 and which also acted as a stop to prevent the further rotation of the coin handling mechanism will force the tail end of said dog inward, causing the nose thereof to be disengaged from the ratchet pinion 100.

The tail of the dog 97 can be forced inward, because as before stated the coin has dropped from the coin pocket, and there is nothing in contact with the pin 99 to prevent the inward movement of the tail end of said dog.

The continued rotation of the coin handling mechanism will bring the edge 81 of the notch 78 into contact with the pin 82 and stop the further rotation of said coin handling mechanism, and when in this position the coin slot 77 is at the top of the device and in alignment with the coin slot 91. During this further rotation of the coin handling mechanism, the dog 97 being out of engagement with the ratchet pinion 100, the shaft 69 will not be revolved and the coin handling mechanism will be in the proper position for the insertion of the next coin. The nose of the dog is of such shape that should it engage the ratchet pinion 100 when there is no coin in the coin pocket, said dog will ride over the teeth of said ratchet pinion, and the pawl 95 always being in engagement with the ratchet gear 94, will prevent any reverse movement of the coin handling mechanism.

On the shaft 69 preferably between the ratchet pinion 100 and the forward bracket 70 is loosely mounted or journalled the bell crank lever 102, one end of which acts as a pointer 103 protected by the shield 104, and the other end has connected thereto a link or wire 105, which is connected with one of the arms of the bell crank lever 106 pivoted to the casing as at 107, the opposite arm of the last named bell crank lever having a pin 108 which registers with the groove 68 between the double flange 67.

As the double spiral 66 is moved along the shaft 69, the pin 108 will be moved to operate the bell crank lever 106, which through the medium of the wire or link 105 will operate the bell crank lever 102, causing the pointer 103 formed from a portion thereof to indicate through an opening 109 in the front end of the casing the relative position of the predetermining mechanism, thus indicating how many coins have been placed in the device, when the capacity of the device is reached, and when another coin should be placed therein.

On the shaft 33 is mounted the sleeve 110, the same being held in its proper position and adjustment by the set screw 111. The

sleeve is provided with a flange 112, and a segmental flange 113, between which is rotatably mounted the connecting dog 114 having a stop 115 to engage the straight edge 116 of the segmental flange and limit the movement of the dog, said stop 115 being normally held in engagement with said straight edge by the spring 117, one end of which is secured to the dog as at 118, and the other end to the sleeve as at 119.

The dog 114 is also provided with a notch 120, which is arranged to register with the flange 66 during certain positions of the predetermined mechanisms or the double spiral 65.

Supposing the controlling valve 27 to be closed upon its seat 26, and the other parts in their relative positions as shown in Figure 3, then to open the controlling valve the operation is as follows:

A coin is placed in the coin handling mechanism and the latter operated to move the double spiral 65 forwardly along its shaft 69, which action will rotate the connecting dog 114 through the medium of the flange 66, thus rotating the shaft 33 and removing the controlling valve 27 from its seat, permitting a flow of gas through the meter. As the gas flows through the meter the diaphragm will be operated, thereby revolving the shafts 5 and motion will be transmitted from said shafts through the joint levers 6, crank 7, shaft 8, worm 9, gear 10, shaft 11, worm 14, gear 15, shaft 16, to the rate wheel shaft 21, then through the rate wheel or gear 49, the gear 50 meshing therewith, the pinions 57 and the gear 58 meshing therewith, which after one complete revolution will cause the single toothed or intermittent pinion 59 to rotate the intermittent gear 60, a portion of a revolution, and through the medium of the pinion 64 will transmit motion to the double spiral 65 to move the same rearwardly along its shaft 69, and when the entire amount of gas is paid for, said spiral will be moved a sufficient distance to cause the flange 66 to again enter the notch 120 in the connecting dog 114, thereby rotating said connecting dog, and the shaft 33 on which it is mounted and closes the valve 27 upon its seat.

Should the controlling valve 27 leak from any cause whatever, and only a sufficient amount of gas is being used to prevent any noticeable effect upon burning lights, the double spiral 65 will be moved rearwardly along its shaft 69, and if the connecting dog was securely fastened to the shaft 33, this action of the spiral 65 will disengage some of the parts, but this possibility is overcome by the construction of the connecting dog 114, and the sleeve on which it is mounted as shown on Figures 5 to 7 inclusive, because the further movement of the spiral 65 will rotate the connecting dog 114 about its sleeve.

110 against the action of the spring 117, and when the pressure of the spiral 65 upon the dog 114 is relieved by the insertion of another coin, said dog will be returned to its 5 normal position by said spring 117, until the stop 115 contacts with the straight edge 116 of the segmental flange 113, and thereafter the connecting dog 114, the sleeve 110 and the shaft 33 will rotate in unison.

10 The amount of gas that will pass through a meter from a leaky valve is relatively small, and might furnish sufficient fuel for a single light, but as soon as a second light is lit, both of the lights will decrease in 15 volume, indicating to the user that it is necessary to place another coin in the device.

When because of any leak in the controlling valve the mechanism of the device has been moved to the position above described, 20 or in other words should the predetermining mechanism be overthrown and the connecting dog 114 rotated against the action of the spring 117, and independent of the shaft 33 beyond its normal position, the same being 25 termed the zero position to the negative side of the zero position, and a coin is then inserted in the device, the predetermining mechanism will be moved forward a predetermined distance, and if that part of gas 30 used is equal to the amount that can be purchased for the first coin, then the insertion of said coin will move the predetermining mechanism to the point which will permit the connecting dog 114 to return to the 35 zero position, but will not open the controlling valve. Thus the device has post-calculated the amount of gas used, and it is necessary to insert an additional coin before the controlling valve will be opened.

40 When the additional coin is placed in the device the predetermining mechanism will be moved further forwardly, and will rotate the connecting dog 114 to the positive side of the zero position, causing the predetermining mechanism to pre-calculate the 45 amount of gas used.

For an example, we will presume that it takes five revolutions of the rate wheel 49 to cause the intermittent gear 60 to move one 50 step, then when sufficient gas has been used to produce five revolutions of the rate wheel or gear 49, the entire train of gears will be operated to move the double spiral 65 rearwardly, the same distance it was moved forward when a coin was inserted in the coin 55 handling mechanism.

If one coin is inserted in the device, the double spiral 65 is moved a predetermined distance along its shaft 69, thus opening the 60 controlling valve and permitting a flow of gas through the meter. As the gas is used, the rate wheel or gear 49 is revolved, thereby revolving the gear 60, the pinion 57, the gear 58 and the intermittent pinion 59, 65 which gradually changes the position of the

single tooth on the intermittent pinion, in this manner calculating the amount of gas to be used, and should half of the amount of gas called for by the insertion of the coin in the device be used, then the single tooth on 70 the intermittent pinion will be moved a half of a revolution. Then should another coin be inserted in the device, the spiral 65 will be moved forward a second predetermined 75 distance, but the train of gears will remain stationary. By the continued use of gas the gears 49, 50 and 58 and the pinions 57 and 59 will be moved the additional half of a revolution until it meshes with the intermittent gear 60, thus moving the same one step, 80 which through the medium of the pinion 64 will move the spiral 65 backward one of the predetermining distances, and the continued use of gas will operate the train of gears in the manner just described, until the spiral 85 65 is moved backward an additional predetermining distance which will close the controlling valve.

From this description it will be noted that although the amount of gas called for 90 by the insertion of one coin in the device has not been entirely used, and another coin is placed therein, it does not affect the amount of gas called for by the insertion of the first coin, and the entire amount which 95 the user has paid for will pass through the meter.

The cover 42 is provided with a catch 121 at its upper end, which is adapted to contact with and overlaps the lug 122 depending from the top wall 40 of the casing, and said cover is further provided intermediate its ends with headed lugs or catches 123 which are engaged by a pivoted latch 124, one end being pivoted at 125 to the 100 casing, and the free end which raises, and brought into contact with the catches 123 being arranged to engage the keeper 126 carried by the rear wall of the casing, and said pivoted latch is raised to the horizontal 105 position by the money drawer 89 when the latter is placed in the casing, and as the upper edge of said drawer is in constant engagement with the latch it is impossible to accidentally displace said latch, thus preventing the opening of the casing until the 110 money drawer is withdrawn, and then it is to be understood it is locked in the casings in any suitable manner.

It is to be noted that I have produced a 120 prepayment device which will permit the delivery of the entire amount of gas to be consumed that has been paid for, will prevent the concern supplying gas from being defrauded either by an unscrupulous person 125 trying to disarrange the mechanism or by the continued use of a small amount of gas that might flow through the meter, caused by a leaky valve and which cannot be injured by placing coins in the device after its 130

capacity has been reached, or by continuing the use of the gas after the amount of gas paid for has been paid.

Of course I do not wish to be limited to 5 the exact details of construction as here shown, as these may be varied within the limits of the appended claims without departing from the spirit of my invention.

Having thus fully described my invention, what I claim as new and useful, is—

1. The coin handling mechanism comprising a body having a coin pocket therein, and provided with a coin slot, said body also having an arcuate notch therein and provided with a groove having an inlet, said arcuate notch acting as the outlet therefrom, a stop lug carried by the body adjacent the inlet to the groove, a ratchet gear carried by the body and means for rotating said coin handling mechanism.

2. The coin handling mechanism comprising a body having a coin pocket therein, and provided with a coin slot, said body having an arcuate notch therein and provided with 25 a groove having an inlet, said arcuate notch acting as the outlet therefrom, a stop lug carried by the body adjacent the inlet to the groove, a ratchet gear carried by the body, means for rotating said body, and a 30 dog pivoted to the ratchet gear provided with means projecting into the coin pocket, whereby said dog will be operated when a coin is inserted in said coin pocket.

3. The coin handling mechanism comprising a body having a coin pocket therein, and provided with a coin slot, said body having an arcuate notch therein and provided with a groove having an inlet, said arcuate notch

acting as the outlet therefrom, a stop lug carried by the body adjacent the inlet to 40 the groove, a ratchet gear carried by the body, means for rotating said body, a dog pivoted to the ratchet gear, and a pin carried by the tail of said dog arranged to move in the arcuate notch and projecting 45 into the coin pocket, whereby said dog may be operated by the insertion of a coin into said coin pocket.

4. In combination with a meter, a housing, 50 a body having a coin pocket therein provided with a groove and having an arcuate notch in communication with the coin pocket and groove, said notch acting as an outlet from said groove, a stop projection carried by the outer face of the body adjacent the inlet to said groove, said body being rotatably and slidably mounted in the coin handling mechanism housing, means carried in the body and projecting through the housing for rotating the same, a pin carried by the housing adapted to coact with the body for stopping the same at each half revolution, a ratchet gear carried by the body, a pawl pivoted to the casing and coacting with the ratchet gear to prevent a reverse movement thereof, a dog pivoted to the ratchet gear, and a pin carried by the tail end thereof working in the arcuate notch and projecting into the coin pocket, whereby 65 said dog may be actuated by the insertion 70 of a coin pocket to cause the nose of said dog to engage the ratchet pinion.

In testimony whereof, I have hereunto affixed my signature.

FREDERICK SMITH,
